UNITED STATES PATENT OFFICE.

GEORGE H. CONRAD AND ADAM WINTER, OF PITTSBURG, PENNSYLVANIA.

CAR-COUPING.

SPECIFICATION forming part of Letters Patent No. 498,625, dated May 30, 1893.

Application filed March 27, 1893. Serial No. 467,830. (No model.)

To all whom it may concern:

Be it known that we, GEORGE H. CONRAD and ADAM WINTER, residing at Pittsburgh, in the county of Allegheny and State of Pennsylvania, have invented certain new and useful Improvements in Car-Couplers, of which the following is a specification.

Our invention has for its object to provide a simple, and effective coupler, in which the coupling can be automatically accomplished and the uncoupling done from the sides of the car.

It has also for its object to provide a coupler of few parts, easily assembled, of great stability and which can be also used in connection with the ordinary pin couplers.

To these ends our invention consists in the peculiar arrangement and combination of parts, all of which will hereinafter be first described in the specification and then particularly pointed out in the claims, reference being had to the accompanying drawings in which—

Figure 1 is a top plan view of our improved coupler with the top plate removed. Fig. 2 is a side view of the same. Fig. 3 is a transverse section of the same on the line 3—3 Fig. 1, and Fig. 4 is a perspective view of one of the coupling hooks detached.

The improved car coupler comprises a draw head formed of a bottom plate A, and a top plate B, preferably of the shape shown which are connected and held spaced apart by the bolts C C and the tubular cuff members D D, the rear ends of such plates being further connected by a king bolt E, to which is pivotally connected the draw bar F, which in the practical arrangement, may be provided with the usual buffer spring devices (not shown). The upper and lower plates are of exactly the same shape with the exception that the front end of the lower plate has an extension or coupling link B' formed integral therewith the end of which is in the nature of a spear point B^x beveled at the front edge at b b, whereby it will ride either above or below the opposing spear point, as the contact conditions may appear, and such point B^x has a longitudinal slot b^x whereby it can be joined with a draw-head having the usual link and pin coupling devices. About centrally the bottom plate has a longitudinal slot A' through which ex-

tends the shank h of a slide bolt H the head of which is bifurcated to form a guideway H', in which is held to operate the crank j of a 55 rock shaft J journaled transversely under the plate A and the car and provided at each end with a lever handle K as shown. The upper or screw end h' of the bolt H enters a threaded socket in a slide block L which we term the 60 "dead block," it being held to slide back and forth on the plate A over the slot A'. This "dead block" when the parts are in their coupled condition, assumes the position shown in Figs. 1 and 2, its front end being at a point 65 slightly to the rear of the front bolts C^x which also form stops to limit the inward or coupling movement of the coupling hooks M M. A pair of these hooks M is mounted in such draw-head and each has at its front end an inturned 70 barb or hook m and at its rear end an inturned finger m' and such fingers m' bear against the rear end of the side faces of the block L.

The hooks M are pivoted upon bolts N N disposed at a point midway the slot A' and such hooks have at such pivotal points semi-circular inwardly extending projections m³ which seat in concaved depressions L' in the sides of the block which are of a length approximately equal the reciprocal thrust movement of such block, and the said block is guided in its movement at its front end between the projections m³ while its rear end has a shank L^x held between two stud bolts l^x l^x as shown.

The upper plate B has its lower front edge beveled as at b³ to facilitate the entrance of an opposing spear head and avoids a thumping action.

From the foregoing description taken in connection with the drawings the advantages and complete operation of our improved car coupler will be readily understood. It will be seen that when the parts are in the position shown in Fig. 1 and an opposing spear head B^x is 90 between the coupling arms M, its barb ends m will engage the base or barb ends of the head B^x and such arms are held to their locked position by the "dead block" L being in its rear-most position. Now when it is desired to uncouple, the lever K is turned in the direction indicated by the arrow, which will rock the shaft J and cause its crank arm to pull the dead block L forward, and as such block is thus slid for-

ward its curved portions L^2 will engage the projections m^3 and cause the arms M to swing with the front ends outward and consequently moving their rear fingers inward, back of the block L, and thereby leave a free passage for the withdrawal of the spear head link portion of the opposing car.

In coupling the arms M can be either thrown inward by a reverse movement of the lever, or it can be automatically effected, as the upper or coupling spear head will engage the dead block, slide it rearward and as it passes back its curved shoulders L^3 will engage the projections m^3 and force the rear arms m' open before the rear end of the block L can strike them.

By beveling the front ends of the spear heads as shown it is obvious that either one or the other will climb up to enter between the arms M of the opposing drawhead.

Having thus described our invention, what we claim, and desire to secure by Letters Patent, is—

1. A car coupling comprising a bottom plate having an integral forwardly extending coupling member, a top plate, a pair of coupling arms pivoted between the upper and lower arms, their forward end having inwardly extending barbs or hook ends and abutting or projecting portions at their pivotal point, a reciprocal slide block disposed between such arms, adapted to engage the said projections

on alternate sides, and means for operating the said slide block, from the sides of the car substantially as shown and described.

2. In a car coupling the combination with the bottom plate A, having a coupling hook at one end, the upper plate B, and the draw bar F, of the pivoted arms M, having coupling barbs at their front end and inwardly projecting lugs m^3 at their pivot point, the block L held to slide between such lugs m^3 and adapted to engage the same in alternate directions and means for reciprocation of the bar L all substantially as and for the purpose described.

3. In a car coupler, the combination with the plate A having a spear head coupling member at its front end, and a longitudinal slot A', the slide bolt H, and the slide block L having projecting shoulders L^2 L^3 , and the crank shaft J connected to the slide bolt H, and provided with a lever or handle K, of the pivoted coupling arms M, having inturned barbs m at their forward end, and inturned fingers m' at their rear end, and formed with projections m^3 on their inner face, adapted to be alternately engaged by the projections L^2 L^3 on the block L, and the upper plate B all arranged substantially as and for the purpose described.
